HELMET

Glenn M. Clohesy, 5813 Helen Ave., St. Louis, Mo.

Filed May 27, 1960, Ser. No. 60,747

Term of patent 14 years

(Cl. D3—13)

FIG. 1.

FIG. 6

FIG. 2.

FIG. 3.

FIG. 4.

FIG. 5.

Figures 3, 4 and 5 are detail transverse sections taken on respective correspondingly numbered section lines of Figure 2.

I claim:

The ornamental design for a helmet, substantially as shown and described.
